SIGNALING COIN RECEPTACLE

Sidney Lempkowitz, Newark, N. J.

Application December 21, 1951, Serial No. 17,797

Term of patent 7 years

(Cl. D34—11)

To all whom it may concern:

Be it known that I, Sidney Lempkowitz, a citizen of the United States, resident of Newark, State of New Jersey, have invented a new, original, and ornamental Design for a Signaling Coin Receptacle, of which the following is a specification, reference being had to the accompanying drawing, forming a part hereof.

Figure 1 is a front elevational view of a signaling coin receptacle, showing my new design;

Figure 2 is a top plan view;

Figure 3 is a rear elevational view; and

Figure 4 is a side view on a reduced scale and slightly reduced in height for convenience in illustration.

I claim:

The ornamental design of a signaling coin receptacle, substantially as shown.

SIDNEY LEMPKOWITZ.
